(57) **CLAIM**

I claim the ornamental design for an improved pull handle for a rolling case, as shown and described.

DESCRIPTION

FIG. 1 is a top plan view of the handle assembly, showing my new design.

FIG. 2 is a bottom plan view thereof.

FIG. 3 is a right side elevational view thereof.

FIG. 4 is a left side elevational view thereof.

FIG. 5 is a rear elevational view thereof.

FIG. 6 is a front elevational view thereof.

FIG. 7 is an isometric view of one example suitcase with the handle assembly extended; and,

FIG. 8 is an isometric view of a second example suitcase with the handle assembly extended.

The broken lines are for the purpose of illustrating possible environment and form no part of the claimed design.
